US00D999172S

(12) **United States Design Patent** (10) **Patent No.:** **US D999,172 S**
(45) **Date of Patent:** **** Sep. 19, 2023**

(54) **COMBINED ELECTRICAL AND
MECHANICAL CONNECTOR**

(71) Applicant: **BELGRAVIA WOOD LIMITED,**
Tortola (VG)

(72) Inventor: **Chi Yin Alan Leung**, Hong Kong (CN)

(73) Assignee: **BELGRAVIA WOOD LIMITED,**
Road Town (VG)

(**) Term: **15 Years**

(21) Appl. No.: **29/815,280**

(22) Filed: **Nov. 12, 2021**

(30) **Foreign Application Priority Data**

May 12, 2021 (CN) 202130283092.X

CLAIM

The ornamental design for a combined electrical and mechanical connector, as shown and described.

DESCRIPTION

FIG. 1 is a top perspective view of an combined electrical and mechanical connector showing my new design.

FIG. 2 is a front view thereof.

FIG. 3 is a rear view thereof.

FIG. 4 is a right view thereof.

FIG. 5 is a left view thereof.

FIG. 6 is a top view thereof.

FIG. 7 is a bottom view thereof; and,

FIG. 8 is a bottom perspective view thereof.

The broken lines shown represent unclaimed subject matter and form no part of the claimed design. The shade lines shown represent surface shading and not surface ornamentation.

1 Claim, 8 Drawing Sheets
